Primary Examiner — Philip S Hyder*Assistant Examiner* — Roselynne Cody(74) *Attorney, Agent, or Firm* — Greenberg Traurig, LLP(57) **CLAIM**

The ornamental design for a tool handle, as shown and described.

DESCRIPTION

FIG. 1 is a rear view of my design;

FIG. 2 is a front view thereof; and,

FIG. 3 is a right side view thereof, the left side view being a mirror image thereof.

The dashed lines in FIGS. 1–3 represent hammer neck and head portions that may extend from the tool handle and form no part of the claimed design. The black dots on the tool handle represent small indentations in the handle.
